SLIDABLE JAW WRENCH

William M. Johnston, Hazlehurst, Ga.

Application August 24, 1948, Serial No. 45,866

3 Claims. (Cl. 81—137)

1

My invention relates to adjustable wrenches of the type wherein a slidable jaw is slidable toward and away from a stationary jaw for engaging work pieces of varying sizes.

With the foregoing in view, an object of my invention is to provide an improved adjustable wrench.

A further object is to provide an improved adjustable wrench which includes means for making quick adjustments of the movable jaw relative to the stationary jaw.

Other objects and advantages reside in the particular structure of the invention, combination and arrangement of the several parts thereof, and will be readily understood by those skilled in the art upon reference to the attached drawing in connection with the following specification, wherein the invention is shown, described and claimed.

In the drawing:

Figure 1 is an elevational view of a wrench according to the invention;

Figure 2 is a fragmentary longitudinal vertical section through the wrench jaws;

Figure 3 is a rear view of the wrench looking from the right of Figure 1, parts being broken away;

Figure 4 is a horizontal sectional view taken substantially on the plane of the line 4—4 of Figure 1;

Figure 5 is a fragmentary elevational view taken substantially on the plane of the line 5—5 of Figure 4, parts being omitted;

Figure 6 is a fragmentary perspective view showing a detail.

Referring specifically to the drawing, wherein like reference characters have been used throughout the several views, the wrench according to the invention as herein disclosed by way of an example, may take the form of a monkey wrench, but is obviously capable of taking the form of other adjustable wrenches. Thus, in the embodiment illustrated, there is provided a stationary jaw 10 having an integral extension or shank 11 extending therefrom at an angle thereto. The free end of the shank or extension 11 may be formed to provide any suitable hand grip 12. A cylindrical stem 13 is fixedly secured in the stationary jaw 10 in any suitable manner and extends therefrom in parallel spaced relation to the extension or shank 11. The lower end of the stem 13 is seated in a forwardly-directed shoulder 14 formed in the upper end of the hand grip 12. A slidable jaw 15 is formed with a longitudinally-extending cy-

2

lindrical bore 16 which slidably receives a stem 13. Thus, the movable jaw 15 is not only slidable on the stem 13 toward and away from the stationary jaw 10, but is also rotatable on the stem 13 into and out of aligned and mis-aligned positions relative to the stationary jaw 10. In the structure illustrated, the stem 13 is provided with an enlarged threaded head 17 which threadedly engages an interiorly-threaded socket 18 formed in the stationary jaw 10. The lower end of the stem 13 is unthreaded and seats in an unthreaded socket 19 formed in the shoulder 14 of the hand grip 12.

The upper inner surface of the shank or extension 11 is preferably longitudinally channelled or concaved, as at 20, to receive the complementary convex surface 21 of the movable jaw 15, whereby to permit sliding and rotatable movement of the movable jaw relative to the stationary jaw. The lower inner surface of the shank or extension 11 is formed with a longitudinally-extending series of rack teeth 22. Likewise, the series of teeth 22 are preferably longitudinally concaved or channelled in rearwardly-offset concentric relation to the channel 20. The rear lower portion of the movable jaw 15 is formed with at least one rack tooth 23 which is complementary to the rack teeth 22 and which is adapted to interengage with such rack teeth 22 upon rotation of the movable jaw 15 on the stem 13 from a mis-aligned to an aligned position relative to the stationary jaw. Likewise, when the teeth 22 and 23 are thus engaged, the movable jaw is thereby locked in an adjusted position relative to the stationary jaw. To adjust the movable jaw 15, it is necessary that it be given a partial rotation on the stem 13 to the position designated in full lines in Figure 3, whereby the jaws are in the mis-aligned position and the rack teeth 22 and 23 are out of engagement. In this position, the movable jaw 15 is freely slidable toward and away from the stationary jaw 10 to adjust the relative space between the jaws. Such movement is illustrated by way of an example in broken lines in Figure 3. As best seen in Figures 5 and 6, and to facilitate the engagement and disengagement of the rack teeth 22 and 23, all of such rack teeth are preferably formed with laterally-tapered ends 24 formed to provide relatively sharp edges 24. Thus, irrespective of whether or not the tooth or teeth 23 is exactly aligned with a channel between adjacent teeth 22, the sharp end edges 24 of the teeth will exert a camming action on the moving tooth or teeth, whereby the same is auto-

matically centered in an appropriate locking channel.

With the jaws in the aligned position, it has been found highly desirable to provide means for locking them against mis-alignment. This is accomplished by the provision of any suitable longitudinally-extending detent on either the stem 23 or movable jaw 15 with a latch carried by the other member and engaging the detent to lock the jaws in the aligned position. In the embodiment illustrated, the detent comprises a longitudinally-extending groove 25 formed in the stem 13. A latch is pivoted on the movable jaw 15 and comprises a latch dog 26 seatable in the groove 25 when the jaws are aligned to prevent rotation of the movable jaw on the stem 13 to a mis-aligned position. The latch dog 26 comprises the free end of a latch lever which is pivoted to the movable jaw 15 by any suitable pintle 27 which spans a slot 28 formed in the movable jaw. The latch includes a finger piece or lever arm 29 which extends forwardly out of the slot 28 where it may be readily grasped by an operator's finger. Any suitable spring means 30 which may be recessed in the slidable jaw 15 bears against the lever arm 29 and loads the latch dog into engagement with the detent-providing groove 25.

While I have shown and described what is now thought to be a preferred embodiment of the invention, it is to be understood that the same is susceptible of other forms and expressions. Consequently, I do not limit myself to the precise structure shown and described hereinabove, except as hereinafter claimed.

I claim:

1. A slidable jaw wrench comprising a shank, a first jaw positioned transversely of said shank adjacent one end thereof and fixedly secured thereto, a second jaw positioned in face to face relation with respect to said first jaw, means mounting said second jaw on said shank for sliding movement toward and away from said first jaw and for limited rotative movement toward and away from said shank, inter-engaging means on said shank and said second jaw for holding said second jaw in any selected position of sliding movement toward said first jaw upon limited rotative movement of said second jaw toward said shank, and a spring biased latch element carried by said second jaw and engageable with said second jaw mounting means upon limited rotative movement of said second jaw toward said shank.

2. A slidable jaw wrench comprising a shank, a first jaw positioned transversely of said shank adjacent one end thereof and fixedly secured thereto, a stem arranged in parallel spaced re-

lation with respect to said shank and fixedly supported in said first jaw and said shank, a second jaw positioned in face to face relation with respect to said first jaw and mounted on said stem for sliding movement toward and away from said first jaw and for limited rotative movement toward and away from said shank, inter-engaging means on said shank and said second jaw for holding said second jaw in any selected position of sliding movement toward said first jaw upon limited rotative movement of said second jaw toward said shank, and a spring biased latch element carried by said second jaw and engageable with said second jaw mounting means upon limited rotative movement of said second jaw toward said shank.

3. A slidable jaw wrench comprising a shank, a first jaw positioned transversely of said shank adjacent one end thereof and fixedly secured thereto, a stem arranged in parallel spaced relation with respect to said shank and fixedly supported in said first jaw and said shank, a second jaw positioned in face to face relation with respect to said first jaw and mounted on said stem for sliding movement toward and away from said first jaw and for a limited rotative movement toward and away from said shank, inter-engaging means embodying rack teeth formed on the portion of said second jaw adjacent said shank and engageable with said rack teeth formed on the adjacent part of said shank for holding said second jaw in any selected position of sliding movement toward said first jaw upon limited rotative movement of said second jaw toward said shank, and a spring biased latch element carried by said second jaw and engageable with said second jaw mounting means upon limited rotative movement of said second jaw toward said shank.
